UNITED STATES PATENT OFFICE.

WILLIS WILLIAM CASSIDY, OF SALT LAKE CITY, UTAH.

DESIGN FOR A HALLOWEEN CANDY.

Application filed June 16, 1928. Serial No. 27,167. Term of patent 3½ years.

To all whom it may concern:

Be it known that I, WILLIS WILLIAM CASSIDY, a citizen of the United States, residing at Salt Lake City, in the county of Salt Lake and State of Utah, have invented a new, original, and ornamental Design for Halloween Candy, of which the following is a specification.

Reference being had to the accompanying drawings, forming part thereof:

Fig. 2 is a side elevation thereof.

I claim:

The ornamental design for a Halloween candy, as shown.

WILLIS WILLIAM CASSIDY.
